UNITED STATES PATENT OFFICE

2,555,874

PHOTOLITHOGRAPHIC PLATE INKING,
DRYING, AND DEVELOPING MACHINEHarry A. Coughlin, St. Louis, Mo., assignor to
John S. Swift Co., Inc., St. Louis, Mo., a corporation of Missouri

Application December 23, 1946, Serial No. 718,063

9 Claims. (Cl. 41—1)

1

In the manufacture of photolithographic printing press plates, a zinc plate is coated with a solution of albumen and ammonium bichromate, which is sensitive to light when dry, and the matter to be printed is reproduced from a photographic negative onto the light sensitized plate by powerful electric light rays. The exposed, printing areas of the sensitized coating are hardened by the light and are insoluble in water, while the unexposed or non-printing areas of said coating are not hardened and are soluble in water.

In developing the exposed photolithographic press plates, the present practice is to pour a developing ink onto the sensitized coating, then spread the ink over said coating with a towel and then rub down the inked surface with a second towel to absorb the surplus ink and to dry the remaining ink. The inked plate is then placed in a pan of water or under a tap and the inked coating hand-rubbed with a large ball of cotton to soften and wash away the soft non-printing areas, leaving the hard printing areas affixed to said plate.

This hand-inking and washing of the photolithographic press plate is a slow and arduous operation, requires a large stock of rubbing towels and cotton and results in the loss of all of the developing ink absorbed by the towels. Another objection is that the hands become stained with ink dyes, which are difficult to remove, inhalation of the chemical fumes causes sickness and loss of time; and physical contact with the ammonium bichromate causes serious poisonous infections which are difficult to cure and cause some employees to seek new occupations.

It is an object of the present invention to provide an automatically operating photolithographic plate treating machine in which a plate or plates are automatically treated by a plurality of separate and distinct devices that are cooperatively associated together in the machine, and such devices perform different and successive individual functions on the plate or plates as the same are moving through the machine.

Another object of the present invention is to provide a photolithographic plate treating machine in which a plate or plates are automatically treated by a plurality of separate spaced-apart distinct devices which perform successive individual functions on the plate or plates as they are continuously moved through the machine.

Another object of the present invention is to devise a machine which will rapidly and efficiently ink, dry and develop photolithographic press

2

plates in one continuous operation without requiring the operator to touch the plate or be in close proximity thereto during such operations, thereby overcoming all of the objections associated with the hand inking and developing of such plates. Other objects are to provide for simplicity and cheapness of construction of said machine and for the automatic operation thereof. The invention consists in the automatic photolithographic press plate inking, drying and developing machine and in the parts and combinations and arrangements of parts hereinafter described and claimed.

In the accompanying drawings, which form part of this specification and wherein like symbols refer to like parts wherever they occur,

Fig. 1 is a plan view of an automatic photolithographic press plate inking, drying and developing machine embodying my invention,

Fig. 2 is a part side elevational and part vertical longitudinal sectional view of said machine,

Fig. 3 is a fragmentary horizontal sectional view on the line 3—3 in Fig. 2,

Figs. 4, 5, 6, 7, 8, 9, 10 and 11 are vertical cross-sectional views taken on the lines 4—4, 5—5, 6—6, 7—7, 8—8, 9—9, 10—10 and 11—11, respectively, in Fig. 2.

Figs. 12 and 13 are enlarged vertical cross-sectional views through the developing head on the lines 12—12 and 13—13, respectively, in Fig. 10,

Fig. 14 is a perspective view of one of the micro switches; and

Fig. 15 is a perspective flow chart, showing the stations of the machine and the electric control circuit therefor.

The photolithographic plate treating machine as embodied in this application is adapted to treat a plate or plates automatically by separate and distinct devices which perform different successive individual functions on the plate or plates as they are continuously moved through the machine. These devices specifically may consist of inking, heating and developing means and are usually arranged in that sequential order for the proper treatment of the plate. The machine includes power operated means that is connected with each of the aforesaid devices and, additionally, with means for continuously moving the plate through the machine. Further, there is provided individual operating means, which means may be in the form of electrical switches or the equivalent thereof in an electrical circuit mounted on the machine adjacent each of the devices, whatever they may be, and operatively connects each of these devices with the power op-

erated means.

erating means and, specifically, such power operating means may consist of electric motor means in the electrical circuit. The aforesaid operating means is carried by the machine, of course, and each of these means is disposed in the path of movement of the plate and is operated by the plate when the plate or plates are moving through the machine. In providing such structural features and arrangement as hereinbefore set forth, the operating means adjacent each of the devices serves to set into operation initially one of the devices and, before that device terminates its period of operation, another device is brought into operation by the next operating means which also maintains the operation of the first treating device while the next device is in operation until after the plate has been treated by the first device at which time the first device will be rendered inoperative. Specifically, the inking device may consist of a plurality of superimposed power driven rollers and the rollers preferably have a gear associated with the same and the diameter of the gear of each roller is substantially the diameter of the roller.

My automatic photolithographic printing press plate inking, drying and developing machine comprises a suitable table 1 with plate receiving, inking, heating and developing stations A, B, C and D arranged in a row thereon along the top thereof in the order named. The plate receiving station A is located at the front end of the table 1 and comprises a fixed horizontal top panel 2 adapted to receive and slidably support a photolithographic printing press plate 3 having a light sensitive top surface coating of albumen and ammonium bichromate on which the matter that is to be printed has been photographically reproduced in the conventional manner above described. Journaled on the table 1 at the discharge end of the plate supporting panel 2 is a pair of upper and lower cross rolls 4 and 5 in position to permit the leading edge of the plate 3 to be entered therebetween, the upper roll 4 operating as an idler hold-down roll and the lower roll 5 being power driven so as to feed said plate to the inking station B.

The plate inking station B comprises a fixed horizontal top panel 7 disposed in the plane of the top panel 2 of the plate receiving station A, an ink fountain or trough 8 disposed crosswise of the line of plate feed and supported above the top panel 7 by means of upright supports 9 fixed to the table 1, a multiplicity of power driven peripherally contacting cross rolls 10 journaled in said supports for transferring the developing ink from said fountain to the upper surface of the plate 3, and power driven feed or pressure rolls 11 journaled in the table 1 and located in openings 12 provided therefor in the top panel 7 immediately below the lowermost inking rollers and in position to engage the under surface of said plate. As shown in the drawings, the feed rolls 11 are spaced below the lowermost, ink applying rolls 10 so as to prevent ink from being applied to the back or under side of the plate.

The inked plate 3 moves from the inking station B to the drying station C which comprises an endless feed belt 13 which is supported at its receiving end on an idler cross roll 14 and at its delivery end on a power driven roll 15, both rolls being journaled on the table 1 and located so that the upper stretch of said feed belt is located in the plane of the plate supporting panel 7 of the inking station B. The plate 3 is held down on the top stretch of the feed belt 13 by means of

cross rolls 16 journaled in the table 1 above the belt supporting rolls or pulleys 14 and 15. The drying station B also includes a battery of overhead infra-red electric heat lamps 17 that are supported in a frame 17a rising from the table and serve to dry the inked upper surface of the plate 3 as it passes through said station on the upper stretch of the endless belt conveyor 13.

The press plate 3 passes from the drying station C to the final or developing station D, which includes a stationary top panel 18 for supporting said plate in the plane of the top stretch of the conveyor belt 13 of said drying station, a pair of spray pipes 19 disposed above and crosswise of the said panel adjacent to the plate receiving end thereof for delivering a spray of water onto the upper surface of said plate as it passes beneath said pipes, and a horizontally movable developing cross head 20 which engages the upper surface of said plate between said spray pipes and the delivery end of said panel. The spray pipes 19 and developing head 20 are supplied with water from a suitable pipe line 21 containing a normally closed electrically operated cut off valve 22 and including a flexible section 21a connected to said developing head so as to permit bodily movement thereof. The water discharged from the spray pipes 19 and the developing head flows through drain openings 24 in the plate supporting panel 18 of the developing station D and over the edges of said panel into a drain tank 25 supported therebelow on a shelf 26 formed in the table 1 and is discharged from said tank through a suitable drain pipe 27.

The developing station also includes a power driven feed roll 28 journaled in the table 1 crosswise thereof and located in an opening 29 provided therefor in the panel 18 between the spray pipes 19 and the developing head 20 and in position to contact the underside of the press plate 3 and move it along said panel. The plate 3 is held down on the feed roller 28 and the top panel 18 by means of an idler roller 30 journaled in the table 1. Upper and lower idler rolls 31 are journaled in the table crosswise thereof adjacent to the delivery end of the top panel 19 of the developing station with the lower roll located in an opening 32 in said panel in position to afford rolling support for the plate 3 and with the lower roll in position to hold the plate down on the lower roll and on said panel.

The feed roll 5 at the receiving end of the plate receiving station A and the feed rolls 11 of the inking station B are all driven by a normally inoperative electric motor 33 mounted on the shelf 26 beneath the receiving station. The driving connection between the motor 33 and the feed rolls 6 and 11 comprises a driving belt connection 34 between said motor and a shaft 35 journaled in a bearing 36 on the motor supporting shelf 26, a sprocket chain connection between said shaft and a driven shaft 38 that is journaled in the table longitudinally thereof and has a worm and worm gear connection 39 with the feed roll 6 and similar driving connections 40 with the feed rolls 11. The feed rolls 11 also have drive gear connections 41 with the lowermost ink applying rolls of the inking station B. By reference to Fig. 6 of the drawings, it will be seen that the diameter of the gears 41 is substantially equal to the diameter of the rollers to which these gears are attached.

The feed belt 13 of the drying station C and the feed roll 28 and developing head 20 of the developing station D are operated by a normally

inoperative electric motor 42 supported beneath the receiving station on the shelf 26 of the table 1. The electric motor 42 has a driving belt connection 43 with a horizontal shaft 44 journaled in a bearing 45 on the shelf 26, a sprocket chain connection 46 between said shaft and a horizontal shaft 47 that extends rearwardly beneath the inking and drying stations and is journaled in bearings 48 mounted on said shelf. At its rear end, the shaft 47 has a sprocket chain connection 49 with the front end of a horizontal shaft 50 disposed longitudinally of the table and journaled in bearings 51 thereon. The front end of the shaft 50 also has a sprocket chain connection 52 with a shaft 53 supported alongside thereof in bearings 54 on the table 1. The shaft 53 extends beneath the driving roll or pulley 15 for the delivery end of the feed belt 13 of the drying station C and the feed roll 28 of the developing station D and has a worm and worm gear connection 55 with said driving roller of said belt and a similar worm and worm gear connection 56 with said feed roller.

Journaled in bearings 57 fixed to opposite sides of the table 1 are vertical shafts 58, that are simultaneously driven in the same direction through bevel driving gear driving connections 59 between their lower ends and a cross shaft 60 journaled in bearings 61 in the table 1, one of said bevel gear driving connections being driven from the shaft 50 by a bevel gear 62 fixed to the rear end thereof. The vertical shafts 58 terminate at their upper ends in crank disks 63 provided with upstanding eccentric crank pins 64 that are linked together by a cross connecting bar 65 whose ends seat on said disks and have vertical openings in which said pins are journaled, whereby said cross bar is moved back and forth crosswise of the machine by the rotary motion of said crank disks. The above developing head 20 comprises a hollow elongated body that is suspended from the crank connecting bar 65 lengthwise thereof for movement therewith by means of inverted channel-shaped straps 66 that are fixed to the top of said head and straddle said bar and are supported thereby by thumb screws 67 that are threaded through the top of said straps with their lower ends seated on the top of said bar. The straps 66 seat in vertical grooves 68 in the sides of the bar 65 and thus force the developing head 20 to move therewith. The hollow developing head 20 is supplied with water through the flexible hose 21^a and has a flat bottom with a multiplicity of discharge openings or perforations 69 therein; and the perforated bottom of said container is covered with a porous rubbing pad 70 which extends upwardly around the sides of the container and is clamped to the top thereof by means of clamping plates 71.

The two electric motors 33 and 42, the infra-red lamps 17 and the electrically operated valve 22 in the water line 21 are controlled by normally closed micro electric switch devices contained in four switch boxes 12, 13, 14 and 15, mounted on the table, each box having pivoted thereon a bell crank lever 76 with a roller 77 adapted to be actuated by the movement of the press plate 3 therebeneath to open the switch or switches associated therewith. The switch box 12 is located near the delivery end of the receiving station A and contains a single normally closed switch 72^a; the box 13 is located near the delivery end of the inking station and contains two nor-

mally closed switches 73^a and 73^b; the box 14 is located near the delivery end of the heating station C and contains three normally closed switches 74^a, 74^b and 74^c; and the box 15 is located near the delivery end of the developing station D and contains two normally closed switches 75^a and 75^b.

The switches are located in an electric control circuit which is supplied by two service wires 10 78 and 79, the wire 78 being provided with a manually controlled push-button cut-off switch 80 which may be mounted on one side of the table 1 adjacent to the receiving end thereof. A line 81 leads from the service wire 78 to one 15 side of the switch 72^a; and a line 82 leads from the other service wire 79 to the motor 33 and thence to the other side of said switch and to one side of the switch 73^a, the other side of which is connected through a line 83 with the service wire 79. One side of the switch 73^b is connected by a line 84 to the service wire 78; and a line 85 connects the other side of said switch with one side of the switch 74^a and also leads to one side of the circuit for the battery of heat lamps. A 20 line 86 leads from the service wire 78 to the other side of the switch 74^a; and a line 87 leads from the other service wire 79 to the other side of the lamp circuit.

A line 88 leads from the service wire 79 to the 30 motor 42 and thence to one side of each of the switches 74^b and 75^a. A line 89 leads from the other service wire 78 to the other side of the switch 74^b, and a line 90 connects said service wire with the other side of the switch 75^a. A 35 line 91 leads from the service wire 79 to the electrically operated stop valve 22 and thence to one side of each of the switches 74^c and 75^b. A line 92 leads from the service wire 78 to the other side of the switch 74^c, and a line 93 leads from said 40 service wire to the other side of the switch 75^b.

After the matter to be printed is reproduced on the sensitized coating of the press plate 3, this exposed plate is placed flatwise on the top panel 2 of the receiving station A with the sensitized coating facing upwardly. The plate is then slid rearwardly on the panel 2 until the leading edge 45 of the plate first passes beneath the roller 77 of the switch actuating lever 76 of the switch box 12 and then into position to be engaged on its under side by the feed roll 5 at the delivery end 50 of said receiving station. This movement of the plate actuates the lever 76 of the switch box 12 and closes the switch 72^a therein, thereby establishing a closed circuit between the service wires 78 and 79 and the motor 33 through the lines 81 and 82 and thus starting said motor and the rotation of the feed roll 5 at the discharge end of the receiving station A, and the inking rolls 10 and feed rolls 11 of the inking station B. The 55 plate is then fed by the feed rolls 10 and 11 through the inking station B where the coated upper surface of the plate is given a uniform coating of developing ink.

The leading edge of the ink coated plate 3 then 60 engages the switch operating arm 76 of the switch box 13 at the discharge end of the inking station, thus closing the two switches 73^a and 73^b in said box before said plate has traveled far enough to permit the switch 72^a to open. The 65 closing of the switch 73^a establishes a holding circuit for the motor 33 after the plate has traveled far enough to permit the switch 72^a to open, this holding circuit being established through the lines 82 and 83, while the closing of the switch 75^b establishes a circuit to the battery of infra-

red lamps 17 through the lines 84 and 85, thus bringing said lamps into operation to thoroughly dry the coating of developing ink on the upper surface of the plate passing therebeneath.

The leading edge of the plate 3 then engages the switch operating lever 76 of the switch box 74 at the discharge end of inking station B, thus closing the three switches 74^a, 74^b and 74^c therein before said plate has traveled far enough to permit the lamp circuit switch 73^b to open. The 10 closing of the switch 74^a establishes a holding circuit for the lamps 17 after the plate has traveled far enough to permit the switch 73^b to open, this holding circuit being established through the lines 87, 85 and 86. The closing of the switch 15 74^b establishes a circuit to the second motor 42 through the lines 88 and 89, thus starting said motor and the operation of the feed belt 13 of the drying station C and the feed roller 28 and the developing head 20 of the developing station D. The closing of the switch 74^c establishes a circuit to the valve 22 through the lines 91 and 92 thus causing said valve to open and water to flow to the spray pipes 19 and the operating developing head 20 of the developing station where 25 the plate is thoroughly washed and developed.

The leading edge of the plate then engages the switch operating arm 76 of the switch box 75 at the discharge end of the developing station D, thus closing the two switches 75^a and 75^b in said 30 box before the plate has traveled far enough to permit the motor circuit switch 74^b and the valve circuit switch 74^c to open. The closing of switch 75^a establishes a holding circuit for the motor 42 through the lines 88 and 93; and the closing of the switch 75^b establishes a holding circuit for the valve 22 through the lines 91 and 93. When the trailing edge of the developed plate passes from beneath the actuating roller 77 of the fourth and final switch box 75, both switches 75^a and 75^b 40 open, thus causing the valve 22 to close and cut off the flow of water to the spray pipes 19 and the developing head 20 and the motor 42 to cut off and stop the operation of the feed belt 13, the feed roll 28 and the developing head 20.

In accordance with common practice, the developed plate is then semi-dried and the printing surface thereof etched with acid and then sponged with liquid gum arabic. As a result of this combination etching and gumming, the non-printing areas are protected from oxidation and will not take ink, while the greasy acid resisting printing areas are receptive to ink.

The hereinbefore described automatic photolithographic printing press plate inking, drying and developing machine has numerous important advantages. It provides means for quickly inking, drying and developing the plate in one continuous process without requiring the plate to be handled during the inking and developing operations and thus entirely eliminates the manual labor heretofore required in performing said operations. It also dispenses with and saves the cost of the rubbing towels and cotton heretofore employed in the inking and developing operations; and it also more uniformly distributes the developing ink over the surface of the plate and results in a material saving in the amount of ink. The plate is sprayed with water to soften the unexposed area of the coating before it is engaged by the developing head; and the rubbing action of said head on the softened areas quickly removes them and the developing ink attached thereto from the plate, leaving the hard exposed printing areas affixed to the plate in clear black designs. An-

other advantage of the above machine is that it is very economical of electricity and water and labor. The above machine also has the great advantage of eliminating the serious infections and chromatic poisoning which heretofore caused loss of time by the operator and the operator to abandon his trade; and it also does not require the operator to be close enough to the work during inking, drying and developing operations to be subject to the nauseating effect of the chemical vapors.

Obviously, the hereinbefore described construction admits of considerable modification without departing from the invention. Therefore, I do not wish to be limited to the precise arrangement shown and described.

What I claim is:

1. A photolithographic plate treating machine in which the plate is automatically treated by a plurality of spaced-apart separate and distinct devices which perform different successive individual functions on the plate while the plate is continuously moved through the machine, the said devices being mounted on the machine in their spaced relationship, means for continuously moving the plate through the machine, power operated means connected independently with each of the devices and with the means for continuously moving the plate through the machine for operating same, operating means adjacent one device for initiating operation of that particular device, operating means adjacent another of the devices for initiating operation of another of the devices and for continuing operation of the operating device, operating means for initiating operation of still another of the devices and continuing operation of one of the operating devices, and operating means adjacent the device at the final stage of treatment for discontinuing operation of the machine.

2. A photolithographic plate treating machine as defined in and by claim 1 wherein the power operated means consists of electric motor means in an electrical circuit.

3. A photolithographic plate treating machine as defined in and by claim 1 wherein the operating means are in an electrical circuit.

4. A photolithographic plate treating machine as defined in and by claim 1 wherein the power operated means consists of electric motor means in an electrical circuit and the operating means is also in the electrical circuit.

5. A photolithographic plate treating machine as defined in and by claim 4 in which the operating means are electrical switches.

6. A photolithographic plate treating machine as defined in and by claim 1 wherein the devices are inking, heating and developing devices respectively.

7. A photolithographic plate treating machine as defined in and by claim 1 wherein the power operated means is electrical motor means and the operating means are electrical switches, and the devices are inking, heating and developing devices respectively, and the motor means and the switches all being in an electrical circuit.

8. A photolithographic plate treating machine as defined in and by claim 1 wherein the devices are inking, heating and developing devices respectively, the inking device comprising a plurality of superposed power driven rollers.

9. A photolithographic plate treating machine as defined in and by claim 8 wherein the rollers are gear driven and the diameter of each gear

is substantially equal to the diameter of each of the rollers.
